J. F. HOFFMANN

AUTOMOBILE LOCK

Filed Nov. 13, 1922

INVENTOR
Joseph F. Hoffmann.
BY Ralph Keusch
ATTORNEY

UNITED STATES PATENT OFFICE.

JOSEPH F. HOFFMANN, OF MAPLEWOOD, MISSOURI, ASSIGNOR TO JOHNSON AUTOMOBILE LOCK COMPANY, OF ST. LOUIS, MISSOURI, A CORPORATION OF ILLINOIS.

AUTOMOBILE LOCK.

Application filed November 13, 1922. Serial No. 600,677.

To all whom it may concern:

Be it known that I, JOSEPH F. HOFFMANN, a citizen of the United States, residing at Maplewood, county of St. Louis, State of Missouri, have invented a certain new and useful Improvement in Automobile Locks, of which the following is a specification, reference being had to the accompanying drawing, forming a part thereof.

10 This invention relates to a certain new and useful improvement in automobile locks and has for its chief object the provision of a readily actuated, efficient device whereby the transmission of the automobile may be positively and securely locked against operation and unauthorized use of the automobile consequently obviated.

With the above and other objects in view, my present invention resides in the novel 20 features of form, construction, arrangement, and combination of parts hereinafter described and afterwards pointed out in the claims.

In the accompanying drawing,

25 Figure 1 is a fragmental longitudinal sectional view of the transmission and transmission-housing of an automobile equipped with a lock embodying my invention;

30 Figure 2 is a fragmental transverse sectional view of the same, taken approximately on the line 2—2, Figure 1;

Figure 3 is a reduced side-elevational view of the same; and

35 Figure 4 is an elevational view, partly in longitudinal section, of a slightly modified form of one of the bolts of the lock.

Referring now more in detail and by reference characters to said drawing, which generally illustrates my invention in preferred form, my new lock is especially adapted for use in connection with automobiles of the Ford type, of which 1 represents the transmission gear-case or housing having the usual top access-affording opening 2, and 3 represents the fly-wheel of the transmission assembly, conjoined to and forming substantially a part of which, as is common, is a ring 4 provided upon its periphery with an annular series of teeth 5.

40 50 Adapted to fit upon, and form a closure for opening 2 of case or housing 1, as best seen in Figures 1 and 2, is a preferably metallic plate 6 provided suitably within its

area and upon its upper or exposed face with an upstanding barrel 7 and upon its under or concealed face with aligning pairs of suitably spaced bolt-supporting eyes 8, 8, and 9—9. As best seen in Figure 1, the bore of barrel 7 is preferably enlarged, as at 10, and disposed for endwise shiftable movement in barrel 7, is a depressible plunger 11 having at its upper end a head 12 accommodated by the bore-enlargement 10.

Interposed in barrel 7 and on plunger 11 between the lower face of its head 12 and the lower wall of bore-enlargement 10, is a coiled spring 13 adapted yieldingly to retain the plunger 11 in normal elevated or raised depressible position. Upon one side, plunger-head 12 is longitudinally grooved or recessed, as at 14, for engagement by the inner end of a retaining-screw, pin, or the like 15 seated in barrel 7 for limiting the shiftable locking and unlocking movements of plunger 11 relatively to barrel 7; and 75 permanently fixed in a housing-enlargement 15 disposed upon barrel 7 preferably diametrically opposite the plunger-retaining pin 15, is a suitable lock 17 comprising a rotary spring-pressed tumbler 18 and bolt 19, the latter being adapted automatically to project into a recess 20 provided in plunger-head 12 when the plunger 11 is depressed and the tumbler 18 and its bolt 19 being key-actuable for withdrawing bolt 19 85 from locking-engagement with the plunger.

At its lower end, plunger 11 is preferably oppositely beveled, as at 21, for actuating engagement with the inner ends of a pair of oppositely disposed bolts 22, 23; supported, 90 respectively, for slideable movement longitudinally of plate 6 and approximately at right angles to plunger 11 by the pairs of eyes 8, 8, and 9, 9, each of which bolts 22, 23, being preferably diametrically formed at its inner or rear end with a surface-groove 24 for co-operation with plunger 11 when the latter is in depressed position, and bolt 23 being formed at its outer or forward end with a tooth or teeth 25 adapted for locking 100 interengagement with teeth 5 of fly-wheel 3 on forward projection or actuation of the bolt 23.

Coiled on bolt 22 intermediate one of the eyes 8 and a pin 26 carried by the bolt, is 105 a bolt-retracting spring 27; and similarly

disposed on bolt 23 intermediate an eye 9 and a pin 28 carried by bolt 23, is a second bolt-retracting spring 29.

In use or operation, plate 6 and its carried parts is disposed in closure-position upon housing 1 and detachably fastened thereto by suitable cap-screws or the like 30, bolt 19 being out of locking-engagement with plunger 11 and plunger 11 and the bolts 22, 23, being yieldingly in normal position or in the position thereof indicated by dotted lines in Figure 1. With the parts in such position, plunger 11 is substantially out of engagement with the bolts 22, 23, bolt 23 is out of engagement with the transmission-member or fly-wheel 3, and the automobile may be operated and driven. On depression, however, of plunger 11 against tension of spring 13, the bolts 22, 23, will, as the plunger 11 is forced therebetween at its beveled lower end 21, be oppositely outwardly projected or actuated against the tension of springs 27, 29,—the one bolt 22 to lockingly engage at its outer end 31 with a wall of housing 1 and the other bolt 23 to engage at its teeth 25 with teeth 5 of the fly-wheel 3. At the same time, on depression of plunger 11, bolt 19 automatically enters the recess 20. Thus, the plunger 11 is automatically locked in depressed position with its lower end 21 disposed between the inner ends of bolts 22, 23, and bolts 22, 23, thereby, in turn, securely and positively locked in engagement with the transmission housing 1 and the transmission-member 3, or in the respective positions illustrated in full lines in Figure 1, and as so engaged, not only is the transmission most efficiently and positively locked against operation, but also the plate 6 and its associated carried parts are similarly locked against removal from the transmission-housing, even on removal of the securing-screws 30. As best seen in Figure 2, the plate 6 is formed upon its under face with lugs 32, which are adapted for engagement with opposite walls of housing 1 at its opening 2 to prevent any twisting removal movement of the plate 6 when the bolts 22, 23, are in locked position and the screws 30 removed.

On tumbler 18 being key-actuated to disengage or withdraw bolt 19 from locking engagement with plunger 11, plunger 11 will at once be returned by its spring 13 to elevated normal position, whereupon bolts 22, 23, will similarly be retracted by their respective springs 27, 29, out of locking engagement with the housing 1 and transmission 3, when the automobile may be operated as is usual.

Preferably bolt 22 is beveled or cut-away at its outer end 31 to conform to the usual formation of the housing wall, and bolt 23 is also preferably beveled, as shown, at its toothed end 25 to clear the fastening-screws

of ring 4 when projected into locking engagement with the transmission member 3.

It might occur that the transmission of the car may come to a standstill with the fly-wheel 3 in such position that the teeth 25 of bolt 23 may not, on projection of bolt 23, immediately register and engage with the teeth 5. To consequently provide against such contingencies and insure locking engagement between the bolt-teeth 25 and the fly-wheel teeth 5 on an attempted operation of the machine with bolt 23 in projected position, the construction of the locking-bolt may be modified as shown in Figure 4 to include a cylindrical body-portion 23^a reduced in diameter at its forward end, as at 33, sleeved upon, and having slot-and-pin connection, as at 34, with which, is a tubular-extension 35 provided at its outer closed end with fly-wheel engaging teeth 25^a, a spring 36 interposed within extension 35 between reduced body-portion 33 and the end wall of the extension 35 functioning to yieldingly project extension 35 away from the body-portion 23^a of the bolt. With such construction, it will be obvious that, while the extension 35 will be both projected forwardly, and retracted rearwardly, with the bolt proper 23^a, should the teeth 25^a fail to register with teeth 5 on projection of bolt 23^a, the extension 35 will be yieldingly further projected on rotary movement of fly-wheel 3 to register and engage at its teeth 25^a with the fly-wheel 3 and thereby lock the transmission of the car against further operation until released.

My new lock is relatively simple in form and construction, may be conveniently installed upon the car, is readily actuatable, and is exceedingly efficient in the performance of its intended functions.

I am aware that changes in the form, construction, arrangement, and combination of the several parts of my new lock may be made and substituted for those herein shown and described without departing from the nature and principle of my invention.

Having thus described my invention, what I claim and desire to secure by Letters Patent is:

1. In combination with an automobile, including its transmission-housing and a rotary member of the transmission-assembly, a lock comprising a plate located upon the transmission-housing, a barrel fixed upon and upstanding at approximately right angles to the upper face of the plate, a pair of spaced aligning bolt-eyes depending from the under face of the plate, a toothed-end bolt supported by said eyes for slidable actuation to engage at its toothed-end with said rotary member to prevent rotary movement thereof, a plunger depressible in the barrel for engagement with and at the opposite end of the bolt for actuating the bolt into, and

retaining the bolt in, locking engagement with the rotary member, and means for yieldingly actuating the bolt out of engagement with the rotary member when released 5 by the plunger.

2. In combination with an automobile, including its transmission-housing and a rotary member of the transmission-assembly, a lock comprising a plate located upon the 10 transmission-housing, a barrel fixed upon and upstanding at approximately right angles to the upper face of the plate, a pair of spaced aligning bolt-eyes depending from the under face of the plate, a toothed-end 15 bolt supported by said eyes for slidable actuation to engage at its toothed-end with said rotary member to prevent rotary movement thereof, a plunger depressible in the barrel for engagement with and at the opposite 20 site end of the bolt for actuating the bolt into, and retaining the bolt in, locking engagement with the rotary member, and a compressible spring coiled on the bolt intermediate said eyes for yieldingly actuating 25 the bolt out of engagement with the rotary member when released by the plunger.

3. In combination with an automobile, including its transmission-housing and a rotary member in the transmission-assembly, 30 a lock comprising a plate removably located upon the transmission-housing, a barrel fixed upon and upstanding at approximately right angles to the upper face of the plate, pairs of spaced aligning bolt-eyes depending 35 from the under face of the plate, a pair of bolts supported by said eyes in end to end alignment for opposite slidable actuation

to engage at their outer ends with said rotary member and said housing for preventing rotary movement of said rotary 40 member and removal of said plate, a plunger depressible in the barrel for engagement with and at the inner ends of said bolts for actuating said bolts into, and retaining the bolts in, locking engagement with the rotary 45 member and the housing, and compressible springs coiled on each of said bolts intermediate the eyes of each of said pairs for yieldingly actuating the bolts out of engagement with the rotary member and the housing 50 when released by the plunger.

4. The combination with an automobile, and its housing, the latter having an opening, of a plate adapted to fit upon the housing and provide a closure for the opening thereof, means for detachably fastening the plate in position upon the housing, a bolt carried by the plate for slidable actuation to engage a member of the transmission, a second bolt carried by the plate for slidable 60 actuation to engage a wall of the housing, a shiftable plunger mounted upon the plate for operable engagement with both said bolts for actuating the same to, respectively, lockingly engage with the transmission-member 65 and with the housing, and lugs on the plate adapted to engage the housing to prevent a twisting removal movement of the plate when said bolts are in locked position and said fastening means released. 70

In testimony whereof, I have signed my name to this specification.

JOSEPH F. HOFFMANN.
